Application May 24, 1941, Serial No. 395,100

4 Claims. (Cl. 36—8.5)

This invention relates to improvements in shoes, and more particularly to improvements in insoles for shoes and the association of the improved insoles with a special type of bottom filler.

In ordinary practice the inner surface of the insole of the shoe is substantially flat. It is believed that some foot troubles such as burning feet and soreness of the joints, particularly the joint between the first metatarsal and the big toe which includes the sesamoid bones, is the result of the flat surface. When shoes have been worn over a long period of time and may be said to be well broken in, there is a slight tendency for the surface of the insole to be shaped to the particular foot. This shaping of the insole which is the result of long wear is relatively slight since shoes are made to maintain their shape. It is conventional practice to use a bottom filler between the insole and outsole but such bottom filler is not readily yieldable under pressure of the foot. Even if sponge rubber or similar cushioning material is used the insole is not readily compressible under pressure of the foot to shape the surface of the insole and form depressions, cavities or pockets which more comfortably fit the joints forming the principal points of support of the foot in the shoe. Metatarsal buttons have been used, either on top of the insole or beneath the insole, so as to raise the surface of the insole between the sides of the foot, but substantially no effort has been made to accomplish a similar result by permitting the sides of the foot to drop and form cavities in the insole.

It is an object of our invention to specially treat the insole whereby selected areas of the insole may be readily depressed under pressure of the foot so that fitting cavities are formed beneath the normal surface of the insole.

It is specifically an object of our invention to improve the construction of shoes by cutting slits in the insole which extend entirely through the thickness of the insole to form areas which will yield and stretch under pressure of the foot so as to shape the insole to the individual foot within a short time after wearing the shoes, such slotted areas of the insole preferably being in the ball area of the sole so as to allow the joint between the first metatarsal and the toe, and the joint between the fifth metatarsal and the toe on the other side of the metatarsal arch, or one of such joints, to form a supporting pocket or pockets in the surface of the insole.

According to our invention the slits in the insole are formed in any desired manner to accom-

plish the desired result, although preferably the slits are very narrow cuts extending substantially transversely of the sole and parallel to each other so that the insole within the desired area is cut into narrow strips which will yield and stretch.

It is a further object of our invention to similarly slit the insole in the region of the heel seat so as to allow the heel of the foot to similarly drop into a cavity. A still further object of our invention resides in the combination of the slit insole with a bottom filler beneath the sole composed of material which is moldable or compressible to receive and retain an impression, such material differing from ordinary sponge rubber which will yield under pressure but springs back to shape after pressure is removed. If such moldable material is placed beneath an ordinary insole it will not so readily take the impression of the foot as the insole resists depression in any particular areas, but when the insole is slit in accordance with our invention the narrow strips of the insole in the slit areas are free to yield under pressure of the foot with respect to the body of the insole and tend to form pockets or cavities in the compressible material placed beneath the insole as well as in the insole itself.

Further objects and advantages of our improvements will be more readily apparent from the following description of further embodiments thereof as disclosed in the attached drawings, in which:

Fig. 1 is a plan view of an insole which has been slit in a special manner to accomplish the desired result;

Fig. 2 is a bottom view of the insole shown in Fig. 1, the layers of filler and fabric reinforcement being partially broken away to expose the underneath layers;

Fig. 3 is a transverse vertical section taken through the ball portion of a shoe having the improved insole and showing the depressions in the inner surface of the insole which result from wearing the shoe;

Fig. 4 is a plan view of an insole relatively thinner than in Fig. 1 and showing a wider spacing of the slits;

Fig. 5 is a sectional view taken on the plane indicated 5—5 in Fig. 1;

Fig. 6 is a transverse vertical section taken on the plane indicated 6—6 in Fig. 2;

Fig. 7 is a plan view of an insole showing a modified arrangement of the slits;

Fig. 8 is a bottom view of the insole shown in Fig. 7;

Fig. 9 is a plan view of an insole showing a still further modified arrangement of the slits in the insole;

Fig. 10 is a sectional view taken on the plane indicated 10—10 in Fig. 8; and

Fig. 11 is a sectional view similar to Fig. 5 but showing a modification in which the slits are cut at an angle.

It is customary practice in the manufacture of shoes to make the inner surface of the insole substantially level transversely of the shoe, particularly at the ball portion of the insole. The weight of the body at the ball portion of the foot rests upon the shoe near the sides of the foot, particularly beneath the large joint between the first metatarsal and the big toe on the inner side of the foot and beneath the small joint between the fifth metatarsal and the little toe on the outer side of the foot. Many foot troubles are the result of improper support of the foot at the metatarsal joints. The large joint between the first metatarsal and the big toe may become particularly painful since this joint transmits pressure through a pair of small sesamoid bones which form the fulcrum over which the weight of the body is transmitted during progression. Attempts have been made to better support the foot at the metatarsal by using metatarsal buttons of sponge rubber placed within the shoe along the top surface of the insole.

In the present invention the shoe is constructed in such a manner as to permit the points of support of the metatarsal to form pockets or cavities below the normal level surface of the insole. The object is to have the foot make an impression upon the insole and the bottom filler, if any, beneath the insole which will accommodate the particular foot and result in a comfortable fit of the shoes upon the feet. It is not practical to cut holes in the insole since the holes might not be properly positioned to fit a particular foot and because such holes would cause objectionable wear of the stockings. The object of our invention cannot be obtained by merely thinning the insole at the particular areas since the fibres of the leather are so closely bonded together that even a thinned area will not readily stretch to form the desired cavity or pocket.

According to the novel improvements disclosed herein, the insole is slit at the desired locations or areas in such a manner that pressure of the foot during the initial wearing of the shoes will result in pressing the slit portions of the insole downward to form a pocket for the joints through which the weight is transmitted. The slitting of the insole may be carried out in various ways but it is desirable to avoid slitting the insole over too large an area or slitting of the insole by cuts which extend longitudinally of the sole since such slitting will tend to impair the strength of the sole in retaining the shape of the lasted shoe. The insole must prevent spreading of the shoe at the ball. The slits or cuts must extend entirely through the thickness of the insole and if carried out in a Goodyear welt shoe in which the bottom of the insole is reinforced by fabric, such fabric may be slit also, simultaneously with the slitting of the insole itself.

Preferably the slits are very small or narrow and do not expand the insole material or result in visible openings through the insole. The cut faces remain substantially in contact and are not spread apart. Preferably the cuts are made straight, although advantageous results may be obtained by employing other forms of cuts which

would be within the scope of our invention in permitting the desired portion of the insole to be pressed into a cavity.

A preferred arrangement of forming the slits or cuts is shown in Fig. 1 in which the area adjacent the sesamoid bones of the foot is slit from side to side by a number of parallel cuts extending transversely of the sole. The spacing of the cuts may vary in accordance with the thickness and stiffness of the leather which forms the insole. In a relatively thin or flexible insole the cuts may be wider apart. In a thicker and stiffer insole the cuts should be closer together. The slitting or cutting results in forming independently flexible strips of the leather insole which are supported at their ends by the uncut body of the insole. Similar slitting of the insole may be carried out in the area adjacent the joint between the fifth metatarsal and little toe on the outer side of the foot. Also advantageous results may be obtained by similarly slitting the heel portion of the insole.

The slitting of the insole also results in increasing the flexibility of the shoes although this is merely incidental to the main object of the improvements disclosed.

Although slitting of the insole as described may be found to be of advantage in any and all types of shoes, the best results are obtained when used in the manufacture of shoes of the type in which a bottom filler is employed between the insole and the outsole such as in the Goodyear welt construction, since the pressure of the foot upon the slitted areas of the insole will tend to form cavities in the bottom filling material. A still further improvement of our invention, however, resides in the use of a special type of bottom filler in combination with the slit insole. The ordinary composition used as a bottom filler is not readily moldable under pressure of the foot. According to this invention a bottom filler is used which is composed of a cellular rubber and cork compound produced in sheet form and from which pieces may be died out to fill the cavity between the insole and the outsole in the Goodyear welt construction. This composition has the special quality of being capable of receiving and retaining an impression, that is, although it is not plastic it can be pressed to take an impression and the impression will remain when the pressure is removed. We have found that very good results are obtained if such a moldable rubber and cork composition or an equivalent material is employed as the bottom filler in association with the slit insole since the impression of the foot will be formed by only a short period of wearing of the shoes. It will be understood that although we prefer to use the particular material described which is capable of taking an impression, other material such as ordinary sponge rubber may be used with advantageous results as compared with ordinary shoes.

The insole generally indicated 10 as shown in Figs. 1 and 2 is illustrated as an insole for a welt shoe, but it will be understood that our improvements are applicable to insoles for any type of shoe construction. The layer of insole material 12 has the sewing ribs 14 turned up from the under side of the sole. A fabric reinforcement 16 may be applied as shown to the under side of the insole within the area surrounded by the ribs 14. A bottom filler 18 may be laid in the forepart of the insole to fill the cavity between the insole 12 and the outsole 20 as shown in Fig. 3. A vamp 22 is attached in the usual man-

ner to make the finished shoe as shown in Fig. 3.

As shown in Fig. 1, an area adjacent the outside of the ball portion of the insole has slits 24 cut entirely through the thickness of the insole layer 12. The slits or cuts may preferably be arranged as shown in Fig. 1 in which a plurality of slits 24 are made extending transversely of the sole and parallel to each other so as to cut the insole into strips 26 which are free to flex and be depressed under pressure of the foot. The area defined by the cuts 24 may be substantially elliptical in shape as shown and the cuts or slits may extend from side to side of the area so that each of the strips 26 is supported at its ends by the body of the insole but is entirely free between its ends with respect to adjacent strips 26. The slits 24 are relatively thin, narrow cuts and do not tend to make visible openings through the insole or tend to expand the sole lengthwise. Furthermore, the slits terminate short of the edge of the insole so that the strength of the margin of the insole is preserved.

A similar area may be slit by the cuts 28 spaced laterally from the slits 24 and defining an area on the inside of the ball portion of the foot. These slits form freely flexible strips 30 which function in a manner similar to the strips 26. In this embodiment the center portion of the insole at 32 does not have any slits or cuts and will therefore not be depressed under pressure of the foot. Instead due to dropping of the sides of the foot the center of the metatarsal is better supported by the uncut portion of the insole.

It may also be advantageous to form slits or cuts 34 in the heel portion of the insole which result in cutting the insole of the heel into the flexible strips 36. These slits 36 terminate inside the margin of the sole in the same manner as the slits 24 and 28.

The layer of reinforcing fabric 16 may or may not be required, but if employed it may be found desirable to extend the slits 24 and 28 through the reinforcing fabric as indicated at 38 and 40 in Fig. 2. If a special fabric which is stretchable lengthwise of the sole is used, it will not be necessary to cut the slits through the fabric.

The conventional type of bottom filler may be employed, but we prefer to employ a bottom filler 18 which is composed of material that is moldable under pressure of the foot whereby in wearing the shoes the area defined by the cuts 24 will be depressed as indicated at 42 in Fig. 3, and the area defined by the cuts 28 will be similarly depressed as indicated at 44 in Fig. 3. It will be noted in this figure that the bottom filler 18 is depressed beneath the depressions, cavities or pockets 42 and 44 which form in the surface of the insole. The moldable material may also be placed beneath the slits 36 in the heel portion of the insole.

The slits which are cut through the insole may vary in spacing in accordance with the thickness and stiffness of the insole material. If a relatively thin and flexible insole is employed, the slits may be widely spaced as shown in Fig. 4 in which the slits 46 are cut through the insole in an area corresponding to the area defined by the slits 24 in Fig. 1. Similarly, the slits 48 may be cut through the insole on the inner side of the ball in an area corresponding to the location of the slits 28 in Fig. 1.

Instead of forming the slits in the spaced areas as shown in Fig. 1, the cuts may extend across the center portion of the insole as shown by the cuts 50 in Fig. 7 formed in the insole 52. The

slits or cuts 50 may be extended through the layer of reinforcing fabric 54 as indicated at 56 in Fig. 8. In order to reinforce the center portion of the insole, a fabric tape 58 may be cemented to the under side of the insole over the fabric layer 54 and extending forwardly and rearwardly of the slits 50 and 56. The tape 58 will tend to reinforce the center portion of the insole by holding the otherwise severed strips of the insole together while leaving the strips free to flex and be depressed on both sides of the reinforcing tape 58. The insole will therefore function in the same manner as the insole shown in Fig. 1.

A still further modification is illustrated in Fig. 9 showing an insole 60 in which an area corresponding to the area defined by the slits 24 in Fig. 1 has been slashed entirely through the thickness of the insole material by the diagonally arranged cuts or slits 62. The area on the inside of the ball is similarly provided with diagonal slits 64 while the center portion of the insole is left uncut at 66. It would not be as desirable to form the slits in a longitudinal direction of the sole since the insole would be weakened in a side to side direction, but the slits may be formed other than straight across the insole as in Fig. 1 such as by making the slits diagonal as shown in Fig. 9, or some similar arrangement.

Although the slits have been shown as cut vertically through the insole, it is not our intention to limit the scope of our invention to the slits being formed in that manner as it may be found desirable to cut the slits at an angle. As shown in Fig. 11 the insole 68 is formed with the slits or cuts 70 which extend through the insole material at an angle to the vertical. The slits 70 are preferably cut to slope inwardly and rearwardly of the insole. This manner of forming the slits may be found more desirable in that the foot does not contact sharp edges of the strips on flexing of the insole.

It is believed to be novel to cut slits entirely through the thickness of the insole from side to side of an area beneath a supporting joint of the foot while otherwise preserving the strength of the insole near the longitudinal center line of the insole so as to permit such selected area to be depressed by pressure of the foot and particularly to combine the specially slit insole with moldable material beneath the insole which will also conform in shape under the foot pressure. Various other modifications may be made in the construction of the insoles from the specific embodiments of the improvements herein disclosed without departing from the spirit of the invention as expressed in the appended claims.

We claim:

1. In a boot or shoe, an insole, an outsole and a bottom filler between the soles, said insole having an area positioned to correspond with the joint between the first metatarsal and the toe on the inside of the foot and having a second area spaced therefrom positioned to correspond with the joint between the fifth metatarsal and the toe on the outside of the foot, each of said areas having slits cut entirely through the thickness of the insole material whereby each of said areas is freely depressible under pressure of the foot to form conforming pockets in the surface of the insole for said joints, the bottom filler beneath such areas being composed of compressible material, said insole outside of said areas being solid and unslit whereby the insole resists depression except in the areas defined by the slits.

2. In a boot or shoe, an insole, an outsole and a bottom filler between the soles, said insole having a substantially elliptical area located to correspond with the position of the joint between the first metatarsal and the toe on the inside of the foot, said area having relatively thin slits cut entirely through the thickness of the insole and extending from side to side of said area whereby the insole material within said area is formed into a plurality of relatively narrow strips supported at their ends by the body of said insole, said strips being freely compressible under pressure of the foot independently of the other strips and said insole having a similar elliptical area located to correspond with the position of the joint between the fifth metatarsal and the toe on the outside of the foot, said area having relatively thin slits cut entirely through the thickness of the insole and extending from side to side of said area in the same manner as in the first area, said insole being solid and unslit outside of said areas, said bottom filler being composed of material which is capable of being compressed under pressure of the foot.

3. In a boot or shoe, an insole, an outsole and filling material between the insole and outsole, said insole being weakened in a predetermined portion of its area spaced inside from the margins of the insole, said weakened portion of the insole being selected to lie beneath the joint between the first metatarsal and the toe attached thereto and being no larger than that required to receive the full pressure of said joint, said

weakened portion of the insole being formed by a plurality of parallel slits cut through the full thickness of the insole and extending from side to side of the weakened area whereby in wearing the shoe the pressure of said joint will depress the weakened portion of the insole and form a cavity, the filling material lying beneath the weakened portion of the insole being composed of material which is capable of being compressed under pressure thereby allowing the weakened portion of the insole to drop and form the cavity.

4. In a boot or shoe, an insole, an outsole and filling material between the insole and outsole, said insole being weakened in a predetermined portion of its area inwardly spaced from the margin of the insole, said weakened portion of the insole being selected to lie beneath a weight bearing portion of the foot and being no larger than that required to receive the full pressure of such portion of the foot, said weakened portion of the insole being formed by a plurality of parallel slits cut through the full thickness of the insole and extending from side to side of the weakened area, the filling material lying beneath the weakened portion of the insole being composed of material which will be compressed to a smaller volume under pressure of the foot thereby allowing the weakened portion of the insole to drop and form a cavity below the normal level of the insole.
